UNITED STATES PATENT OFFICE

165,935

TELEVISION CABINET

Joseph D. Portanova, Los Angeles, Calif., assignor
to Hoffman Radio Corporation, Los Angeles,
Calif., a corporation of California

Application January 24, 1951, Serial No. 13,938

Term of patent 3½ years

(Cl. D56—4)

To all whom it may concern:

Be it known that I, Joseph D. Portanova, a citizen of the United States, residing at Los Angeles, State of California, have invented a new, original, and ornamental Design for Television Cabinet, of which the following is a specification, reference being had to the accompanying drawing, forming a part hereof, in which drawing:

Figure 1 is a perspective view of a television cabinet, showing my new design; and

Figure 2 is an enlarged fragmentary sectional view taken on line 2—2 of Figure 1.

The opposite side of the cabinet of Figure 1 is the same as the side shown, and the rear is plain.

I claim:

The ornamental design for a television cabinet, as shown and described.

JOSEPH D. PORTANOVA.
